AMPLIFIER SYSTEM

John Hardwick, West Drayton, and Eric Lawrence Casling White, Hillingdon, England, assignors to Electric & Musical Industries Limited, Hayes, Middlesex, England

Application June 30, 1936, Serial No. 88,094
In Great Britain July 9, 1935

4 Claims. (Cl. 179—171)

The present invention relates to electric circuits for modifying frequency response in amplifiers and the like.

For certain purposes, for example in the transmission of television picture signals, it is required to provide an amplifier or other circuit arrangement which favours high frequencies by transmitting the lower frequencies with relatively less amplification or more attenuation. In such cases it is also required to avoid substantial phase shift or at least to avoid phase shift which is other than a mere time displacement of the signals as a whole.

It is an object of the present invention to provide a circuit arrangement such that both of the requirements set forth above are fulfilled.

The present invention accordingly provides a circuit arrangement such for example as an amplifier in which means arranged to favour certain frequencies of applied signals relatively to other frequencies are provided for effecting frequency-response correction wherein, in order to avoid substantial phase shift, there are provided two or more stages each arranged to effect a part of the desired frequency-response correction, the arrangement being such that distortion of the wave form of said signals due to phase shift introduced by one of said stages is neutralized or substantially reduced by a compensating phase shift introduced by one or more of the remaining stages.

The invention will be described as applied to the correction of the fall in response at high frequencies which manifests itself in certain forms of television apparatus due to the finite size of a scanning aperture; it is to be understood that when scanning is by sweeping a spot of light over an object, or a cathode ray spot over a mosaic screen, the dimensions of the scanning spot are the equivalents of those of a scanning aperture.

In the course of the following description, reference will be made to the accompanying drawing, which illustrates in Figs. 1 and 2, two arrangements according to the invention.

45 The response R of a photo-cell, in conjunction with a scanning aperture of diameter d , to a sine-wave variation of object brightness of wave length λ , is proportional to

$$50 K \sin \frac{\pi}{K}$$

where $K = \lambda/d$. The response will be zero when $d = \lambda$. If the linear speed of scanning is s , a variation of object brightness of wave length λ causes an electrical oscillation of frequency

$$55 f = \frac{s}{\lambda}$$

60 to be set up in the output circuit of the photo cell.

The response R is, therefore, equal to zero at the frequency

$$f_0 = \frac{s}{d}$$

Furthermore, in the neighborhood of the frequency f_0 , the response will be below that at lower frequencies.

Now

$$10 K \sin \frac{\pi}{K}$$

can be expressed as a series

$$15 K \left[\frac{\pi}{K} - \frac{\pi^3}{6K^3} \dots \right]$$

and hence R is approximately proportional to

$$1 - \frac{A}{K^2}$$

where A is a constant. It follows that in order to correct for the fall in response as the frequency f_0 is approached, it is necessary to introduce a correction which varies approximately with the square of the frequency.

Reference is now directed to Fig. 1 of the accompanying drawing, which shows an amplifier in which means are provided for introducing a correction of the desired character; the amplifier comprises two amplifying valves 3 and 4 which are both of the screen grid type. The picture signals to be corrected are applied to the control grid of the first valve 3 through a condenser 5. The anode of the valve 3 is connected to the positive terminal of a source (not shown) of anode current, the negative terminal of which is earthed, through a coil 7 having an inductance L in series with a resistance 8 of value R_1 . The anode of the first valve 3 is also connected to the control grid of the second valve 4 through a coupling condenser 9, and the control grid of the second valve 4 is connected to the cathodes of the two valves and to earth through a grid leak 10 and a biasing source 11. The anode of the second valve 4 is connected to the positive terminal of the anode current source through the primary winding of a transformer 12 and a resistance 13 of value R_2 arranged in series, the transformer winding being arranged between the resistance 13 and the anode of valve 4. One end of the secondary winding of the transformer 12 is connected to the end of the primary winding remote from the anode of valve 4, and the other end of the secondary winding is connected to an output terminal 14. The windings of the transformer have a mutual inductance M, and it is arranged that

$$55 \frac{L}{R_1} = - \frac{M}{R_2}$$

Now in a television system, the frequency f_0 may be 4 megacycles or more and it is desired

60

that the amplifier should have a substantially uniform response up to some frequency below but in the neighborhood of 4 megacycles. The capacity of the anode of the first valve with respect to earth, the value of which capacity will be referred to as C , is effectively in parallel with the inductance L and resistance R_1 . This capacity may be of the order of 20 micro-micro-farads and the magnitude of L and R_1 are arranged to have such values that the circuit 7, 8 and the anode-to-earth capacity is always working well below its resonant frequency.

The output from the first valve of the circuit above described is proportional to $(R_1+j\omega L)$, and it will be noted that the output is dependent, both in amplitude and phase upon the frequency. The output from the second valve is, however, proportional to

$$20 \quad (R_1+j\omega L)(R_2+j\omega M) = R_1R_2 \left\{ 1 + \left(\frac{L}{R_1} \right)^2 \omega^2 \right\}$$

the amplitude of output being proportional to a constant plus the square of the frequency, as required, but the resultant phase angle thereof being zero.

The correction thus obtained in the two-stage amplifier described is accordingly of the required form and shows no phase change.

In an alternative arrangement according to 30 the present invention, which will be described with reference to Fig. 2, the correcting networks are associated with a single stage of amplification, but the correction is nevertheless carried out in two stages, one in the grid-cathode circuit 35 of the valve and the other in the anode circuit.

Referring to Fig. 2, the valve 15 is again a tetrode and the signals to be corrected are applied between the control grid and earth by means of condenser 16, and grid leak 17 and biasing battery 18. The cathode of valve 15 is connected to earth through a resistance 19 of value R_1 having a condenser 20 of value C_1 connected in parallel. The anode circuit of valve 15 includes a network 12, 13 connected and arranged as described with reference to Fig. 1, the value of resistance 13 being R_2 and the mutual inductance between the transformer windings being M . The negative terminal of the anode current source (not shown) is connected to earth as in Fig. 1, and it is arranged that

$$R_1C_1 = -\frac{M}{R_2}$$

It can be shown that, in the arrangement of Fig. 2, if an alternating potential difference of constant amplitude is applied between the control grid of valve 15 and earth, the current in the valve increases with increase in frequency of the applied potential difference in accordance with the law $(1-j\omega C_1 R_1)$ provided that

$$\frac{1}{g}$$

is small compared to R_1 and

$$65 \quad \frac{1}{j\omega C_1}$$

where g is the mutual conductance of the valve. Since the impedance of the anode circuit in-

creases with increase of frequency in a similar manner, the required square-law correction is obtained. Further, as in the arrangement of Fig. 1, the total resultant phase shift is zero.

The increase of amplification with increase of frequency is limited in the cathode circuit as the impedance of condenser C approaches

$$\frac{1}{g}$$

10 This is usually desirable, provided that limitation occurs outside the operating frequency range. The impedance of circuit 7, 8 in Fig. 1 may be limited if desired by shunting inductance 8, or the whole circuit 7, 8, by a resistance of suitable value. Similarly, in the arrangement of either of Figs. 1 or 2, a limiting resistance may be arranged in shunt either with the primary winding of the transformer, or with this winding and resistance 13 in series; such a limiting resistance is shown at 21 in Fig. 2.

15 The invention is not limited to television amplifiers, and many further applications of the invention will occur to those versed in the art.

Having now described our invention, what we claim and desire to secure by Letters Patent is:

1. An amplifying system comprising means to feed signals accompanied by frequency and phase distortion to a thermionic amplifier, and substantially a non-capacitive impedance means associated with the thermionic amplifier for further increasing the frequency distortion and neutralizing the phase distortion of the signals.

2. In combination, a thermionic tube having at least a cathode, a control electrode, and an anode, a parallelly connected resistor and condenser connected between a cathode and an output terminal, means to supply signalling energy having components of different frequency to the control electrode and said output terminal, means to supply energy serially through a plurality of non-capacitive impedances to the anode, means for deriving energy both inductively and directly from a junction point of said plurality of impedances whereby the derived energy has a phase shift which is linear with respect to frequency and terminal means connected to said last named means.

3. A two-stage amplifier comprising a first stage having a non-linear frequency response and a non-linear phase shift response, a second stage having a non-uniform frequency response and a non-linear phase response, the phase response of said second stage having a value complementary to said first phase response, whereby the overall phase response is linear.

4. An amplifier system comprising a thermionic tube having at least a cathode, a control electrode and an anode, a non-linear frequency and phase shift response means including a capacitive reactance circuit connected between said cathode and said control electrode, and a phase distortion neutralizing substantially non-capacitive impedance circuit having a non-linear frequency response connected to said anode.
